UNITED STATES PATENT OFFICE

2,603,314

CONSTRUCTION AND ARRANGEMENT OF
RESTAURANTS

Thomas Maldwyn Lewis, London, England, assignor to Conveyor Cafeterias, Limited, London, England

Application February 20, 1948, Serial No. 9,914
In Great Britain February 25, 1947

5 Claims. (Cl. 186—1)

1

This invention relates to restaurants of the conveyor type adapted to expedite the delivery of meals and to enable more meals to be served with the use of a given floor area than is possible by more conventional arrangements.

It is a feature of such constructions that they should be as compact as possible so as to reduce to a minimum the floor area which they occupy and this requirement may give rise to difficulty in the way of customers entering or leaving the travelling system at the entrance and exit points due to there being insufficient room for the customers to pass comfortably or conveniently between the tables and seats.

The object of the present invention is to overcome this difficulty in a simple and convenient manner without any sacrifice of floor space, and according to the invention there is provided means whereby the distance between the tables and seats may be increased at the entry and/or exit point.

According to one feature of the invention the seats may preserve their normal line of travel while the tables may be moved away from the seats.

According to a further feature of the invention the tables may preserve their normal line of travel while the seats may be moved away from the tables.

In either of the foregoing modifications the movement may be automatic or may be made at the will of the customer.

Further features of the invention will be apparent from the description given hereafter.

The accompanying drawings illustrate one convenient mode of carrying out the invention.

Figure 1 is a perspective view showing the upper part of a portion of a restaurant in accordance with the invention.

Figure 2 is a cross-section on a larger scale showing one set of conveyors for tables, seats, and foot rests.

Figure 3 is a cross-section on a still larger scale showing one form of seat and seat guide.

Figure 4 is a section on the line 4—4 of Figure 3.

Figure 5 is a side elevation of a table on the left side of the arrangement shown in Figure 1.

Figure 6 is a section on the line 6—6 of Figure 5.

Figure 7 is a diagrammatic plan view of an arrangement for automatically moving the table, particularly illustrating the guide controlling this movement.

Figure 8 is a diagrammatic plan view of a modified arrangement providing for the movement of the table, and

Figure 9 is a diagrammatic plan view of an

2

arrangement embodying means for providing automatic movement of the seats.

In carrying the invention into effect in one convenient manner the improved restaurant is formed with an endless conveyor *a* supported upon suitably spaced rollers *b* in its upper length or run and carrying slats or slabs *c* of plastic or other suitable material serving as tables. The rollers *b* roll along the longitudinally extending track of the frame member *b'* which therefore constitutes supporting means for the conveyor *a*. Adjacent this conveyor there is provided a second and parallel conveyor *d* carrying the seats *e* for the customers and also supported on its upper length or run by rollers *f* rolling along a frame or track *f'* which constitutes the supporting means for conveyor *d*, and between the two there may be a further conveyor *g* supported on its upper run by the rollers *h* rolling along track or frame member *h'* and serving as a moving platform on which the customers may rest their feet while seated at the tables, it being understood that all the conveyors travel at the same linear speed and are mounted upon and driven by any suitable means.

In one construction in accordance with the invention the slats or tables *c* may be movable transversely of the conveyor by being mounted on rollers arranged in guides or by other suitable means and at the entry and exit points of the restaurant cam guides of suitable form are provided engaging means upon the movable tables so that at these points the tables will be moved automatically across the conveyors and away from the seats thus leaving ample room for the customers to pass in and out at these points between tables and seats.

In a further construction in accordance with the invention the tables may be made to preserve their normal line of travel and the seats *e* may be movable transversely of their conveyors and may be engaged by suitable guide means so that the seats will be moved away from the tables, this arrangement being shown at the bottom part of Figure 1.

In the foregoing arrangements the movement of the tables relatively to the seats is effected automatically but in place of this arrangement the tables or the seats may be mounted so as to be movable as required by the customers themselves, and in such case it may be convenient to provide suitable limiting means whereby the extent of movement in either case may be limited. In the case where the movement is automatic this may be effected in both directions by suitable guides or in some cases the movement may be positively effected in one direction by the guides and the return movement may be

effected by springs. Moreover, such springs may also be employed for the return movement in the case where the positive movement in one direction is effected by the customers themselves.

In the particular construction shown in Figures 2, 5 and 6, the tables are arranged for automatic movement and each table consists of a slat or slab *c* of suitable plastic material having a dove-tailed slot therein by which it may be slidably carried on a complementarily formed portion of the member *c'* having depending lugs *c²* secured to the conveyor. One end of the table has secured to it, as by the screw *c³*, a depending member carrying a roller *c⁴* adapted to travel in a channel guide *c⁵* which runs parallel to the conveyor except at each end, where it is shaped to produce the necessary movement of the table at the exit and entry ends. The end of the table remote from the guide *c⁵* is supported by a guide rail *i* which runs parallel to the guide *c⁵*.

If it be required to move the table by hand, the channel guide *c⁵* would be widened to permit the movement required, and the guide rail *i* would be set in from the edge of the table at each end. The seats can be moved transversely if desired in the same manner as the tables.

In Figures 3 and 4 one convenient form of seat is illustrated in which the seat cushion *e* is carried in a trough-like member *k* having guides *k'* receiving rollers *l* carried by a member *m* secured to the conveyor, the seat thus being movable transversely of the conveyor upon the rollers *l*. When it is required that the movement of the seats be effected automatically, this may be done if desired in a different way from the method used for the tables by providing a series of rollers *k²* located at one edge of the seat and secured to the supporting structure, and such rollers are maintained in contact with the seat as it passes in front of them by means of a spring *k³* attached at one end to the seat and at the other end to the carrier member *m*.

An alternative method of movement would be to control the seat by a light spring such as *k³* against which the seat would be movable by the weight of the customer, the extent of movement being controlled by stops at the ends of the guides *k'*.

As indicated in Figure 7 the channel guide *c⁵* and the guide rail *i* are parallel and the roller *c⁴* carried by each of the table slabs *c* moves between the walls of the guide *c⁵* and at the entry and/or exit points the guide deviates so that the roller in following the same moves the table slabs *c* transversely of the line of movement.

In Figure 8, as illustrated, the arrangement in which the guide rail *i* is straight and the guide member *c⁵* is formed with a deviation that at the entry and/or exit point is disposed closer to the guide rail *i* so that as the conveyor *a* moves the table *c* the customer is able to push the table transversely of the line of movement and the guide rail *i* being straight would thus be set in from the outer end of the table as shown.

In Figure 9 is illustrated the arrangement for automatically moving the seats, and as shown the series of rollers *k²* embody a plurality of rollers causing the seats to move transversely of their line of travel. As clearly shown in this figure with the conveyor *d* moving, the movable seat portions comprising the cushion carried in the trough-like member *k* are moved transversely of the member *m* carried by the conveyor. The rollers engaging the surface of the seats cause

them to move transversely and stretch the spring *k³*, and which spring holds the seats against the rollers so that when the path defined by the position of the rollers *k²* widens the seats are moved in a transverse direction toward the tables.

It will be understood that the foregoing details of construction are given purely by way of example to indicate the nature of the invention and not to limit its scope and the number of conveyors comprised in a restaurant and the directions in which the conveyors travel (that is, whether in horizontal or vertical planes) may be varied depending upon any practical requirements that may have to be fulfilled.

I claim:

1. A restaurant including laterally spaced, elongated parallel supporting means, said supporting means being disposed at different heights, an endless conveyor supported by and movable over each of said supporting means, horizontally disposed table constituting means carried by the highest of said conveyors and horizontally disposed seat constituting means carried by the other conveyor, both of said conveyors travelling at the same linear speed, and means for increasing the transverse distance between the seating means and the table means so as to facilitate the passage of customers therebetween.

2. A restaurant including at least one endless conveyor constituting in its upper length a continuously moving horizontal table, a stationary support arranged immediately beneath the upper length of the conveyor and extending substantially throughout the length thereof, an endless conveyor at one side of said moving table and at a lower level than the table and constituting in its upper length a continuously moving horizontal line of seats and a stationary support for the upper length of the seat conveyor arranged immediately therebeneath, the table and seats travelling at the same linear speed, and means for increasing the transverse distance between the seats and the table adjacent at least one end of the upper lengths of the conveyors to facilitate the passage of customers therebetween.

3. A restaurant as claimed in claim 2 including means mounting the seats for transverse movement relative to their conveyor, the increase being effected by movement of the seats transversely of their conveyor, the tables preserving a normal line of travel.

4. A restaurant as claimed in claim 2 including means mounting the tables for transverse movement relative to their conveyor, the increase being effected by movement of the tables transversely of their conveyor, the seats preserving a normal line of travel.

5. A restaurant including at least one continuously moving horizontally disposed table and at least one continuously moving horizontally disposed seat travelling at the same linear speed as the table and disposed in parallel spaced relation thereto, individual supporting means for the table and seat including means providing for transverse movement of at least one of these relative to the line of travel.
